UNITED STATES PATENT OFFICE.

ROBERT M. COX, OF PHILADELPHIA, AND THOMAS BEVERLEY KEIM, OF READING, PENNSYLVANIA; SAID KEIM ASSIGNOR TO SAID COX.

CHAIR.

SPECIFICATION forming part of Letters Patent No. 461,238, dated October 13, 1891.

Application filed August 14, 1891. Serial No. 402,626. (No model.)

To all whom it may concern:

Be it known that we, ROBERT M. COX, a resident of Philadelphia, Pennsylvania, and THOMAS BEVERLEY KEIM, a resident of Reading, Pennsylvania, both citizens of the United States, have invented certain Improvements in Chairs, of which the following is a specification.

The object of our invention is to provide a chair for use on shipboard, in which the seat can be rotated on its standard or be rigidly secured thereto, or the parts can be so adjusted that they may be readily turned by the occupant, but prevented from turning by accident.

In the accompanying drawings, Figure 1 is a vertical section of our improved chair. Fig. 2 is a section on the line 12, Fig. 1. Fig. 3 is a perspective view of the seat-carrier, and Fig. 4 is a perspective view showing the clamping-wedges detached.

In chairs for use on ships it is desirable to have them revolve, but at the same time to prevent them from accidentally revolving while the ship is lurching. By applying sufficient friction between the base and the seat-carrier the chair can be revolved by the person occupying it but it will not revolve accidentally.

Referring to Fig. 1, A is the base of the chair, which is secured to the floor in any suitable manner, and has a hollow standard B. Adapted to this standard is a seat-carrier D, slotted at d d for the reception of the wedges E E. In the present instance two wedges are used and arranged opposite each other. These wedges are pivoted to lugs d' on the interior of the carrier D and bear against the inner surface of the standard B, as clearly shown in Fig. 1.

Adapted to the interior of the carrier D is a wedge-shaped block F, (clearly shown in Fig. 4,) having inclined ways f f, adapted to the backs of the wedges E E, as shown in Fig. 1. This block is preferably provided with guiding flanges f' for the wedges. Connected to the block is a head G, having a screw g; which passes up through a nut H. This nut has a suitable handle h by which it is turned, and is locked as regards vertical motion by a set-

screw or series of set-screws i, which in the present instance form part of the seat-frame I. These screws i pass in an annular groove in the nut, as clearly shown in Fig. 1. The nut H has a cap h', which covers the top of 55 the carrier D, as shown in Fig. 3. The seat-frame I is secured to the seat I' in any suitable manner.

It will be seen that the seat can be raised or lowered in the standard B, and the seat-carrier can be entirely removed from the standard for repairs or for cleaning, leaving simply the base and standard.

The person using the chair can adjust the seat by simply passing the hand under the 65 seat and operating the handled nut, putting more or less friction between the parts, as desired.

We claim as our invention—

1. The combination, in a revolving chair, of 70 the hollow standard, the seat-carrier, wedges carried by the seat-carrier, and a block adapted to operate the wedges, with mechanism for moving said block, substantially as described.

2. The combination of the hollow standard, 75 the seat-carrier adapted thereto, wedges pivoted to said seat-carrier, a vertically-movable block acting on said wedges, a screw connected to said block, and a nut on the seat-carrier engaging with the screw, whereby on the turning 80 of the nut the wedges will be moved against or withdrawn from the standard, substantially as described.

3. The combination of the hollow standard, 85 the seat-carrier, wedges pivoted thereto and adapted to bear upon the interior of the standard, a wedge-block, a screw secured thereto, a handled nut adapted to said screw, and a seat-frame, with pins on said seat-frame confining the nut against vertical movement, substantially as described.

In testimony whereof we have signed our names to this specification in the presence of two subscribing witnesses.

ROBT. M. COX.
THOMAS BEVERLEY KEIM.
